ELECTRICAL GROUND CLAMP

Chalmon John Shrader, Henrico County, Va.

Application March 31, 1943, Serial No. 481,367

3 Claims. (Cl. 173—273)

1

This invention relates to electrical ground clamp or connections and more particularly to arc welding connections.

One of the objects of this invention is the provision of a clamp adapted to be connected to various sizes of conductors.

Another object of this invention is the provision of an adjustable clamp.

Other objects and features will more fully appear from the following description and accompanying drawing, in which:

Fig. 1 is a vertical side view; Fig. 2, a sectional proportional side view; Fig. 3, a top plan view, and Fig. 4, an electrical circuit.

Referring to the drawing, an angular male member 1 is disposed in slidable fashion in an angular female member 2 and is provided with a ball and socket joint 3 to which is connected a contact 4.

A contact 5, similar to 4, is connected to a ball and socket joint 6 disposed in one end of a rod 7 slidable through end 8 of the female member 2, and adapted to be secured by a lock-nut 9.

Contacts 4 and 5 are held together by a spring 10; the ends of which are respectively secured to members 1 and 2.

A contact member 11 is secured near one end of member 1 while a contact 12 is disposed near one end of member 2 as shown in Fig. 1. Contact member 11 engages slot 13 throughout its length to prevent circumferential displacement with respect to members 1 and 2. Welding of member 11 to sleeve 1 through slot 13 of member 2, may be accomplished by applying one terminal of a source of current to sleeve 1 through such slot and the other terminal of the source to member 11, thereby completing a circuit and effecting the welding of member 11 to sleeve 1, in the manner well known in the resistance welding art. Furthermore, it is obvious that the shank of part 11 may be circular and have its end threaded to engage a correspondingly threaded hole in sleeve 1.

Female member 2 is provided with a toothed end 14 adapted to scrape rust and non-conducting materials from a conducting material; while a swiveled hook 15 having a pair of resilient legs 16—17 is adapted for being clamped to the device at any suitable point so that said hook may be secured to an object and thus support the device.

An electrical conductor 18 is connected to male member 1 and adapted to conduct electrical current.

It is obvious from the foregoing that if a piece of metal is to be welded then by pulling members 1 and 2 apart, against spring tension, contacts

2

4—5 open and may be closed upon said metal thus securing the device to the metal in electrical circuit.

To secure the device, for instance, inside an angular metal bar C, members 1 and 2 are pulled against spring tension and contacts 11—12 move toward each other and may be inserted in tube and electrical contact thus made; as illustrated in the schematic electrical diagram of Fig. 4, in which current passes through conductor A from generator B, through the angular bar C and device and returning to the generator via conductor 18.

Magnetic blocks 20 are respectively secured to members 1—2 and adapted to hold the device in a fixed position against any material that is attracted by said blocks.

Having described this invention, what is claimed is:

1. In an electrical connector, a tubular member having a slot through its side wall longitudinally of said member, a hollow elongated member, a contact mounted on said member and extending through said slot, a tension spring within said hollow member having its ends secured to said members slidably fitting within said tubular member, each of said members having an arm rigidly extending laterally from the free end thereof, a first gripping element mounted upon the free end of one arm, a rod connected with the free end of the other arm for adjustment toward and from said element, means for securing said rod and its arm in adjusted position, and a second gripping element mounted upon the end of said rod adjacent said first element.

2. In a connector as defined in claim 1, each of said gripping elements being universally pivotally mounted upon said one arm and rod.

3. In an electrical connector, a tubular member, having a slot through its side wall longitudinally of said member, a hollow member telescopically fitting said tubular member, a tension spring within said hollow member and having its ends secured to said members, respectively, a first clamp element having a shank extending through said slot and there secured to said hollow member, a second clamp element having a shank secured to said tubular member adjacent its end receiving said hollow member, a parallel arm projecting laterally from the free end of each of said members, a rod mounted on one said arm for adjustment toward and from the other arm, means carried by said arm and securing said rod in adjusted position, and cooperating contact elements universally pivoted upon said other arm and an end of said rod.

4. In an electrical connector, a tubular member, having a slot through its side wall longitudinally of said member, a hollow member telescopically fitting said tubular member, a tension spring within said hollow member and having its ends secured to said members, respectively, a first clamp element having a shank extending through said slot and there secured to said hollow member, a second clamp element having a shank secured to said tubular member adjacent its end receiving said hollow member, a parallel arm projecting laterally from the free end of each of said members, a rod mounted on one said arm for adjustment toward and from the other arm, means carried by said arm and securing said rod in adjusted position, and cooperating contact elements universally pivoted upon said other arm and an end of said rod.

CHALMON JOHN SHRADER.
